Gilbert C. Gettelman, Hartford, Wis., assignor,
by mesne assignments, to Hamilton Watch
Company, Lancaster, Pa., a corporation of
Pennsylvania

Application July 14, 1948, Serial No. 147,568

Term of patent 3½ years

(Cl. D1—12)

To all whom it may concern:

Be it known that I, Gilbert C. Gettelman, a citizen of the United States, residing at 384 West Sumner Street, Hartford, in the county of Milwaukee and State of Wisconsin, have invented a new, original, and ornamental Design for Display Clock, of which the following is a specification, reference being had to the accompanying drawing, forming part thereof.

Figure 1 is a front elevation of a display clock showing my new design, the opposite side being similar in appearance.

Figure 2 is a bottom plan view thereof.

The broken lines are shown for illustrative purposes only.

I claim:

The ornamental design for a display clock, as shown and described.

GILBERT C. GETTELMAN.
